UNITED STATES PATENT OFFICE

120,912

DESIGN FOR A COMBINED ILLUMINATING LAMP SHADE AND SUPPORTING BRACKET

John A. Heckman and Bengt Arvidson, Elmhurst,
Ill.

Application March 13, 1940, Serial No. 90,882

Term of patent 7 years

To all whom it may concern:

Be it known that we, John A. Heckman, a citizen of the United States, residing at Elmhurst, in the county of Du Page and State of Illinois, and Bengt Arvidson, a citizen of the United States, residing at Elmhurst, in the county of Du Page and State of Illinois, have invented a new, original, and ornamental Design for a Combined Illuminating Lamp Shade and Supporting Bracket, of which the following is a specification, reference being had to the accompanying drawing, forming part thereof.

Figure 1 is a perspective view of a combined

illuminating lamp shade and supporting bracket embodying our new design.

Figure 2 is a top plan view thereof.

Figure 3 is a front elevational view thereof.

Figure 4 is a rear elevational view thereof.

Figure 5 is an end elevational view taken from the left of Figure 1.

We claim:

The ornamental design for a combined illuminating lamp shade and supporting bracket, substantially as shown.

JOHN A. HECKMAN.
BENGT ARVIDSON.
